UNITED STATES PATENT OFFICE.

FRANCIS P. BESSETTE, OF WICHITA, KANSAS.

SCREEN-DOOR INSECT BRUSH AND DESTROYER.

Application filed April 1, 1921. Serial No. 457,776.

To all whom it may concern:

Be it known that I, FRANCIS P. BESSETTE, a citizen of the United States, residing at Wichita, in the county of Sedgwick and State of Kansas, have invented new and useful Improvements in Screen-Door Insect Brushes and Destroyers, of which the following is a specification.

The object of this invention is to provide a screen door with a fly brush which will be automatically operated by opening and closing of the door to brush the flies from the door and thereby prevent their entry into the house. Incident to the construction of device adopted, many of the flies are actually destroyed while others are merely brushed off the door.

Referring to the drawings, forming a part of this specification, and wherein like numerals of reference designate corresponding parts throughout the several views,

Fig. 1 is a view in front elevation of a screen door with the invention applied thereto.

Fig. 2 is a vertical sectional view taken on the line 2—2 of Fig. 1, and

Figs. 3 and 4 are perspective views in detail of parts of the invention.

In the drawing, reference numeral 1 designates the door frame, 2 the screen door of the usual swinging type, and 3 the wire netting of the door. At a suitable point on the door is attached a shelf 4, formed preferably of sheet metal, and to this shelf is attached at its lower end the fly brush, the upper end of which brush is attached to a follower 5. The brush is composed of a plurality of transverse strips 6 formed from wire screening, and at staggered points adjacent strips are connected together by wire clips 7, so that when distended, the brush assumes a cellular form with diamond shaped cells. The upper and lower extreme strips 6 are attached to the follower and shelf respectively by clips 8. To the central portion of the follower 5, is attached an operating cord 9 which extends upwardly over a pulley 10, thence horizontally through a guide 12 on the outer and upper corner of the door, thence through a pulley block 14 hung from the door frame at a point adjacent the said guide 12, and thence downwardly along the frame of the door, where the free end is secured in a manner to be described. The said pulley roller 10 is journaled on a rod or wire 15 having its ends

bent at right angles and secured in turned over ears 16. These ears are cut from the material of the supporting bracket 17 and when bent up produce the opening in which the pulley 10 operates. The said supporting bracket 17 has its rear end 18 bent downwardly at substantially right angles and this angular end portion is secured by screws or the like to the upper edge portion of the door, substantially centrally of the upper portion thereof. To the outer end of the bracket 17 is hinged a downwardly extending member 19, and a portion thereof 20, extends above the bracket 17 for a purpose to be described. To the lower end of the member 18 is hinged a horizontal tripping element 21, past which the follower 5 trips when the latter is raised and by which it is suspended after tripping. The member 21 has a right-angular front end 22 which engages the member 19 to maintain member 21 in the horizontal.

To the door frame, substantially centrally of the upper frame member, is attached a bracket 24, to the outer end of which is hinged a member 25, limited in its outward movement by a stop extension 26 formed on said bracket member 24, all for a purpose to be described.

When the operation is understood, it will be found that it is advisable, if not really necessary, to have some slack in the operating cord, to permit operation of the device as the door begins to open. This may be provided for by securing the end of the cord to the frame with as much slack as is necessary given to the cord, with or without the inclusion of a coil spring for compensating purposes, or, as illustrated in the drawing, the free end of the cord 9 may be attached to the upper end of a light coil spring 30 having an enlarged lower end 31 and passing through a guide eye 32, the distance from said eye to the lower end of the spring corresponding to the amount of slack required.

In operation, the parts are assumed to be in the position illustrated in the drawing, with the follower 5 engaged with and supported by the trigger member 21, as in Fig. 4. Immediately the door is opened, the trigger element 20 as shown in Fig. 2 engages member 25, and continued outward movement of the door causes the trigger element 21 to be withdrawn from beneath the follower 5, whereupon, the weight with the added tension of the cellular structure 6

will cause the said cellular brush to collapse and fold together at the lower end of the device and upon the shelf 4 as shown suggestively by the dotted line 5'. All of this takes place before the door is opened any appreciable amount, and, therefore, the aforementioned slack is necessary in the cord 9. Immediately the brush begins to collapse, the spring 30 begins to move upwardly in the guide eye 32 until the enlarged lower end of the spring 31 engages said eye 32. Of course, the spring is not essential, but is inserted as a compensator. Upon slight further opening movement of the door, 15 the trigger element 20 moves out of contact with the member 25 and these parts return to initial position.

Thus it will be observed that the collapsing of the brush not only shoos the flies 20 away, but also causes some of them to be caught between the strips 6 and to be crushed thereby. The proportion of flies 25 brushed away and those crushed will depend upon the rapidity of movement of the brush in collapsing, and this can be regulated in an obvious manner by increasing or decreasing the number of strips 6, the weight thereof, or by the interpositioning of some additional operating means such 30 as springs and the like, not shown.

After collapsing of the brush, continued movement of the door in being opened and after the slack has been taken up in the cord, 35 will cause the brush to be again extended to the position shown in the drawing, and wherein the follower 5 trips past the trigger 21 and the latter falling behind said follower, supports the brush in extended position. Then, after being so set, closing of the door 40 produces no effect, except to cause the slack to take place in the operating cord, as by the spring 30 dropping down through the guide eye 32 to the position shown. It will be understood that as the door approaches its 45 closed position, the trigger element 20 engages, tilts, and falls behind the member 25 without displacing the trigger element 21 from engagement with the follower 5.

Having fully described the invention, 50 what is claimed is:—

1. The combination with a swinging door, of an insect brush, means for moving the brush in one direction, and means whereby the brush is moved in the opposite direction at the moment the door approaches a predetermined position.

2. The combination with a door, of an insect brush movable in one direction of its own weight, and means whereby the brush is moved in the opposite direction through the action of moving the door.

3. The combination with a door, of a foldable insect brush, and means whereby the brush is folded and unfolded through the opening of the door.

4. The combination with a door, of a foldable insect brush having a tendency to fold, means normally holding the brush unfolded, means for causing said means to release the brush to permit its folding upon initial 70 opening of the door, and means operable during continued opening movement of the door for unfolding the brush and causing the same to be held by said first means.

5. The combination with a door and its frame, of an insect brush thereon, means for holding the brush in one position, means for causing release of the brush from the first means on initial opening movement 80 of the door, means for causing movement of the brush in one direction when so released, and means between the door and frame for returning the brush to its first position through continued opening movement of the door.

6. The combination with a door and its frame, of an insect brush thereon, means on the door for holding the brush in one position, means on the frame for causing release of the brush from the first means on initial opening movement of the door, means for causing movement of the brush in one direction when so released, and means between the door and frame for returning 90 the brush to its first position through continued opening movement of the door.

7. The combination with a door and its frame, of an insect brush on the door, means on the door for holding the brush in one position, means on the frame for causing release of the brush from the first means on initial opening movement of the door, means for causing movement of the brush in one direction when so released, and a 100 flexible element between the brush and frame for returning the brush to its first position through continued opening movement of the door.

8. The combination with a swinging door and its frame, of a brush support thereon, a self-folding insect brush on said support, a cord attached to said brush and said frame for unfolding the brush during opening movement of the door, means on the door adapted to automatically engage with and hold the brush unfolded, and means on the frame for disengaging said means to permit the brush to fold on initial opening movement of the door.

9. The combination with a screen door, of a collapsible cellular insect destroying device thereon adapted to be set and released through movement of the door.

In testimony whereof I have hereunto set my hand in presence of two subscribing witnesses.

FRANCIS P. BESSETTE.
